UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC BELL.

Application filed March 1, 1919. Serial No. 280,012.

To all whom it may concern:

Be it known that I, REUBEN B. BENJAMIN, a citizen of the United States, residing at Chicago, in the county of Cook and State of Illinois, have invented new and useful Improvements in Electric Bells, of which the following is a full, clear, concise, and exact description, reference being had to the accompanying drawing, forming a part of this specification.

My invention relates to improvements in electric bells, and one of the objects of my invention is to provide an electric bell in which all of the hammer-actuating mechanism is enclosed in a sealed casing, the actuating mechanism being mounted upon and supported by the casing in such a manner that the casing may be opened for inspection and repair of the parts without disturbing or displacing any of the operating mechanism of the bell.

Other objects and advantages of my invention will appear more fully in the accompanying specifications and drawings.

For the purpose of disclosing my invention I have illustrated certain embodiments thereof in the accompanying drawings, in which—

Fig. 1 is a plan view of a bell embodying my invention and having the cover for the casing removed and certain parts shown in section;

Fig. 2 is a sectional view taken on the line 2—2 of Fig. 1;

Fig. 3 is a detail view showing means for adjusting the gong;

Fig. 4 is a plan view of another form of bell embodying my invention;

Fig. 5 is a plan view of the bell illustrated in Fig. 4, with the cover removed;

Fig. 6 is an elevational view of the construction shown in Fig. 4, the view being taken from the lower side of Fig. 4, and parts being broken away to show the interior construction; and

Fig. 7 is a side elevational view of the construction shown in Fig. 4, the view being taken from the left, and parts being broken away to show the interior construction.

In the embodiment illustrated in Figs. 1 to 3, I provide a cylindrical casing having a side wall 1 and the bottom 2 preferably formed in one piece. At one point on the side wall of the casing there is formed a

boss 3 having an opening through which the leading-in wires are brought. This opening is internally screw-threaded to receive the end of the conduit pipe which leads to the casing and is thereby effectually sealed, or the opening may be sealed in any other suitable manner if desired. A second boss 4 is formed on the side wall of the casing, which is internally screw-threaded to receive a plug 5. A pair of screws 6 and 7 extend through the casing at this point, for a purpose more fully hereinafter described. These screws also pass through a lock plate 8, which may be slightly tilted by the screw 9 which passes therethrough and bears against the wall of the casing to lock the screws against rotation. The casing has its side wall bulged or extended at 10, and within the casing this bulged portion is channelled at 11 to form an upper and lower bearing for a rock shaft 12, which passes through an opening in the top of the bulged portion of the casing and has its lower end seating in the bottom of the bulged portion. The top portion of the casing surrounding the rock shaft is provided with a countersunk opening 13 having a tapering bottom and adapted to receive a suitable packing 14 which surrounds the rock shaft 12 and is held in position by a countersunk screw 15 surrounding the rock shaft. By this arrangement the point at which the rock shaft passes into the casing is sealed against the entrance of dust or moisture. The upper end of the rock shaft is bent at right angles and bowed to form a spring hammer arm 16, which at its free end carries the striker or hammer 17 for the bell. The operating mechanism of the bell is all mounted on and within the casing and comprises an electromagnet having a pair of windings 18, the cores 19 of which are secured to a yoke 20, which in turn is secured by a pair of screws 21 to a pair of lugs (not shown) projecting upwardly from and formed integrally with the bottom 2 of the casing. An armature 22 lies opposite the poles of the coils 18 and at one end is non-rotatably secured to the rock shaft 12, so that any movement imparted to the armature will operate the rock shaft and, in turn, operate the striker arm 16. The opposite or free end of the armature has connected thereto a retractile spring 23. One end of this spring is hooked through an opening in the inner end of the

- screw 6 and the opposite end passes through an opening in the armature and is hooked over a plate 24, which plate is larger than the opening in the armature. This arrangement permits the spring to rotate with the screw 6 and at the same time connects the spring and armature together. This spring acts to retract the armature from the poles of the magnet when the circuit through the magnet is broken, and it will be noted that by the arrangement of the screw 6 adjustment of the tension of this spring may be made from the exterior of the casing by removing the plug 5 from the nipple 4.
- 15 Mounted within the casing on a pair of lugs 25 extending upwardly from and integrally cast with the bottom 2 is an insulating base 26, on which are mounted a pair of binding plates 27 and 28 carrying binding-posts for 20 the leading-in wires. These binding-posts are separated from one another by a rib 29 formed on the base. The binding plate 27 has upstanding therefrom a lug 30, to which is secured a flat spring 31 carrying one contact 32 of the circuit-breaker of the operating magnet. The free end of this spring rests upon an insulating tip on the end of the screw 7, so that by adjusting the screw 7 the spacing of the contacts of the circuit-breaker may be adjusted, and it will be noted that this screw may be adjusted from the exterior of the casing simply by removing the plug 5 of the nipple 4. The terminal plate 28 has an upstanding lug 33 to which is secured the flat contact spring 34 of the circuit-breaker, which spring at its free end carries a contact 35 co-operating with the contact 32, and is also provided with an insulating tip 36 adapted to pass through an 35 elongated opening 37 in a pin 38 extending from the free end of the armature 22, so that as the armature is attracted by the operating magnet the contacts 32 and 35 will be separated. At the same time, due to the 40 fact that the opening 37 is slightly elongated, a certain amount of movement of the armature will be permitted before these contacts are separated. Formed on the base 26 is a buffer 39 against which is adapted to 45 strike the free end of a buffer spring 40 secured at one end to the armature 22 and having its free end slightly separated from the armature. This spring acts as a buffer and takes up a certain amount of the jar on the 50 armature due to its return to normal position when the circuit-breaker is opened each time.
- 55 The interior of the cylindrical wall 1 of the casing is screw-threaded to receive the 60 threaded flange 41 of the cover plate 42, which is thereby secured in position. The edge of the casing wall and the edge of the plate are bevelled, as at 43, to insure a close fit at this point.
- 65 The gong 44 is supported by the cover plate, and to this end there is formed on the cover plate a hollow split post 45, which is exteriorly tapered and screw-threaded to receive a clamping nut 46. A stem 47 is mounted in the post and has the gong eccentrically secured thereto at its upper end by a bolt 48. Due to the eccentric mounting of the gong post the gong may be adjusted to and from the striker 17, and after the proper adjustment has been made, by 70 setting the nut 46 the stem will be securely clamped in the post and the gong held against displacement.
- In Figs. 4 to 7, inclusive, I have illustrated a modified form of my invention. In the 75 structure illustrated in these figures I provide a casing, preferably cylindrical in shape and having the cylindrical walls 49 and the bottom 50 preferably cast in one piece. Formed in the walls at a suitable 80 point is a boss 51 through which the leading-in wires are brought and which is internally screw-threaded to receive the conduit pipe, which thereby effectually seals the casing at this point; or the casing may be 85 sealed in any other desired manner. The body of the casing is provided with integrally cast lugs 52 having openings for attaching screws, and the upper edge of the walls 49 has an inwardly extending flange 53 90 to form a seat for the cover plate 54. At intervals the side wall 49 is thickened or has inwardly extending lugs 55 adapted to receive the clamping screws 56 for the cover. At one point on the wall 49 I form a lug or 95 in-turned extension 57, which in effect forms a portion of the flange 53. The purpose and advantage of this lug will appear more fully hereinafter.
- All of the operating parts of the bell are 100 mounted within the casing, and for operating the bell I provide the usual electromagnet, comprising the coils 58 having their cores 59 secured by screws 60 to a yoke 61, which in turn is secured by screws 62 105 to a pair of lugs 63 cast integrally with and extending upwardly from the bottom 50. Opposite the poles of the magnet is arranged an armature 64 split and drilled at 110 one end and clamped to and supported by a rock shaft 65, which shaft is journaled at its bottom in a post 66 formed integrally with and extending upwardly from the bottom 50 and the lug 57, through which lug 115 the shaft passes. The post 66 and the lug 57 are spaced apart to accommodate the pivoted end of the armature 64 and form the bearings for the rock shaft 65, which shaft at its upper end is turned at right angles 120 and bowed to form the striker arm 67 of the bell, having a suitable striker 68 secured at its free end. At the point where the shaft passes through the lug or casing a countersink opening is formed around the shaft, 125 this opening being tapered at its bottom 130

and adapted to receive a suitable packing 69, which packing is held in position by a screw 70 surrounding the rock shaft and screwing into the countersink opening. An 5 insulating base 71 is mounted within the casing on a pair of upwardly extending lugs 72 and carries the two binding-post terminal plates 73 and 74 to which the leading-in wires are connected. The binding- 10 post terminal plate 73 has an up-turned projection 75, into which is threaded a screw 76 carrying one of the contacts 77 of the circuit-breaker. An angle plate 78 is secured to the base 71, and on the upwardly extending portion 15 of this plate is mounted a leaf spring 79, the free end of which is provided with a hook or lip 80 which engages over an insulating finger 81 secured on the free end of the armature 64, whereby the spring 79 acts 20 as a retractile spring for the armature. A branch spring 82 is secured to the spring 79 and carries at its free end the second contact 83 of the circuit-breaker. One end of the magnet coils 58 is connected to the binding-post terminal 73; the opposite end is 25 connected to the spring 79, which in turn is connected to the opposite terminal plate 74; and it is obvious that as the armature is attracted by the magnet the circuit of the coils 30 will be broken between the contacts 77 and 83 to produce the usual vibratory movement of an electric bell.

The cover plate 54 of the casing carries 35 the gong 84, and to this end is provided with a post 85 having a screw-receiving opening at its top to receive the securing screw 86 for holding the gong in position. This cover has a notch 87 formed in its periphery, which notch is large enough to accommodate 40 the rock shaft 65 and its surrounding screw 70, but the edge of the notch rests on the top face of the lug 57, so that when the gasket 88 is placed in position and the cover plate clamped home by means of the screws 56 the

cover will make a sealed joint with the casing at all points, and, due to the fact that the only opening in the casing, which is the opening accommodating the rock shaft 65, is packed, the casing is sealed against moisture and dust. 45

50 While I have illustrated and described in the accompanying drawings and specifications certain embodiments of my invention, it will be understood that the invention may take other embodiments or changes may be 55 made in those illustrated and described, without departing from the spirit of the invention as set forth in the appended claims.

Having thus described my invention, 60 what I claim as new and desire to secure by Letters Patent, is:—

1. An electric bell comprising a sealed casing, bell-wringing mechanism mounted wholly within said casing, a removable cover for said casing having a hollow, split, externally threaded post formed on the exterior thereof, a stem mounted in said post, a gong eccentrically mounted on said stem, and a nut secured over said post for clamping 65 said stem in position. 70

2. An electric bell comprising a sealed casing, electromagnetic bell-ringing mechanism including the hammer mounting arranged within and entirely mounted on said casing, a removable cover plate for the casing removable without displacing any of the bell-ringing mechanism, said casing having a chamber formed on the exterior of the side wall, adjusting screws for the bell-ring- 75 ing mechanism extending through the side wall of the casing into said chamber, and a cover for said chamber whereby the bell-ringing mechanism may be adjusted from 80 the exterior of the casing. 85

In witness whereof, I have hereunto subscribed my name.

REUBEN B. BENJAMIN.
